UNITED STATES PATENT OFFICE.

ANDREW M. COYLE, OF NEW YORK, N. Y., ASSIGNOR TO OTIS ELEVATOR COMPANY, OF JERSEY CITY, NEW JERSEY, A CORPORATION OF NEW JERSEY.

ELEVATOR-DOOR LOCK.

1,102,477.

Specification of Letters Patent.

Patented July 7, 1914.

Application filed November 13, 1905. Serial No. 286,984.

To all whom it may concern:

Be it known that I, ANDREW M. COYLE, a citizen of the United States, residing in the city of New York, in the county of New York and State of New York, have invented a new and useful Improvement in Elevator-Door Locks, of which the following is a specification.

My invention relates to door locks, particularly such as are used for locking elevator doors, and one of its objects is the provision of simple, efficient, and safe means for locking a door.

A further object of my invention is to provide means connected with the car for operating said door lock.

Another object of the invention is the provision of a circuit closer to co-act with said operating-means and control coöperating means.

Other objects of my invention will appear hereinafter, the novel combinations of elements being set forth in the claims.

In the accompanying drawings, Figure 1 represent a longitudinal section of the locking mechanism in unlocked position; Fig. 2 is a similar view, but showing the parts in locking position; Fig. 3 shows the operating means with the circuit closer co-acting therewith; Fig. 4 is a plan view of the device shown in Fig. 3; Fig. 5 shows a modification in that a lock in open position for a sliding door is shown; Fig. 6 shows the same in locked position; Fig. 7 is a sectional view of the device shown in Fig. 5 taken on the line *a—a* and looking in the direction of the arrows; Fig. 8 is an enlarged detail section on the line *b—b* of Fig. 6 and looking in the direction of the arrows; and Fig. 9 shows diagrammatically an elevator system with my invention applied thereto and in particular a means for operating the electro-magnetic cam on the car and for controlling the car operating means.

1 designates the lock casing which is to be placed in the jamb of the door or secured thereto. 2 is the keeper casing to be placed in a swinging door such that when the door is closed, the said casings shall be opposite each other as shown in Figs. 1 and 2. The face plates 3 and 4 of the respective casings are provided with openings 5, 6, 7, and 8.

Adapted to slide through the upper opening 6 in the face plate 4 of the keeper cas- 55 ing is a latch 9 to which is secured the latch

bolt 10. The latch bolt 10 is supported at its right-hand end in the rectangular recess 22 in the lug 11, and is prevented from being moved from this recess by the lock plate (not shown) which is adapted to be secured 60 to the keeper casing at the points 23 and 24.

The latch 9, which is adapted to strike against a cam face 47 (Fig. 3) and engage the thrust plate 43, is provided with a shoulder 19 against which bears a spring 18, the latter passing around the fixed lug 21 and held in place by the stop 20. The spring tends to force the latch outwardly or to the left but this movement is limited by the head 13 of lever 37' herein shown as pivoted 70 about at the central right hand portion of the keeper casing, which head is engaged by the lug 12 when the latch is moved to the left. In order to move the latch to the right, or entirely within the keeper casing, a knob 75 connected to the spindle 15 to which the lever arm 14 is rigidly secured, must be turned to move the head 13 to the right. At the same time a downwardly extending lever arm 16 which is also rigidly secured 80 to the spindle 15 is moved to the left so that the head 17 shall strike against and move the sliding bar 25 to the left. This movement is limited by the projections 26 striking against the lug 28 which has a rectangular recess to receive said sliding bar 25. Its movement in the opposite direction is limited by the projections 27 (Fig. 2). When the bar 25 is in its left-hand position, that is, when the latch is withdrawn as 90 shown in Fig. 1, the enlarged portion 29 of said bar is substantially flush with the face plate of the keeper casing as shown in Fig. 1.

In substantial alinement with the sliding bar 25 is a sliding locking bar 30 in the lock casing 1. The movement of the lock bar 30 to the left is limited by the lug 31 fixed to the casing 1. It will be seen that when the bar 25 is in its extreme left-hand position 100 and the door is closed, the shoulder 45 engages the projection 31 while the right-hand end of the bar 30 is substantially flush with the surface of the face plate 3 and opposite the head 29 of the bar 25.

The bar 25 is guided by the opening 8 while the bar 30 is guided by the opening 7. The downward projection on the bar 30 may also have a bearing 32. At the upper part of the latch casing 1 is a bar 42 mov- 110

- able in the opening 5 in substantial alignment with the bar 10, and provided with an enlarged portion 43 which may be square or rectangular, or any other desired shape.
- 5 The bar 30 is pivoted at 35 to the arm 36 of a lever 37 which is pivoted to the latch casing 1 at 39. The upper arm 38 is pivoted to the bar 42 at 41. Fixed to the lever 37 is some means such as a weight 40 for moving the shoulder 45 against the stop 31 and placing the exposed ends of the arms 42 and 30 substantially in the same plane or parallel with the face of the plate 3. The parts then assume the positions shown in Fig. 1. Obviously the details and arrangement of parts may be varied, as desired.
- When the spindle 15 is moved anti-clockwise or released, the comparatively strong spring 18 will act to move the bar 10 to the left and so also the bar 42. The bolt 30 and bar 25 will simultaneously be moved to the right until the shoulder 46 abuts against a portion of the latch casing 1 and the projections 27 engage the lug 28. Furthermore, 25 if desired, the parts may be so constructed that the spring 18 will contact with a portion of the keeper casing 2 and the weight 40 may be stopped by a portion of the lock casing.
- 30 It will be seen that the levers 37 and 37' have substantially a parallel motion and that when the lever 37' is moved counter-clockwise to release the latch bar 10 and the sliding bar 25, the spring 18 will act to latch and lock the door as shown in Fig. 2. But when the lever 37' is moved in the opposite direction the bolt 10 and bar 25 are positively actuated to unlatch and unlock the door as shown in Fig. 1.
- 40 Adapted to pass through an opening 34 in one or both sides of the lock casing 1 is a bar 33 which may be guided by the bearing 32. When the door is unlocked, that is, when the parts assume the positions indicated in Fig. 45 1, the path of travel of the bar 33 is obstructed by the projection 32', but when the door is locked as shown in Fig. 2, the rod 33 is free to move and when moved into or through the lock casing 1 the door cannot be 50 opened. If this is attempted the shoulder 45 will immediately engage the lock bar 33 and further movement of the lock bolt 30 prevented. When the spindle 15 is rotated in a clock-wise direction to a certain extent 55 the upper end 13 of the lever arm 14 will engage the projection 12 to positively actuate the latch bar 10 to the right. At the same time the lower end 17 of the lever arm 16 will engage the bar 25 to positively actuate 60 the same to the left. This movement is transmitted to the lock bar 30 to positively move the latter to the left to unlock the door. This movement may be transmitted still further to force the bar 42 to the right and 65 move the latch 9 to the right. The weight

40 in such case may be omitted, but it is preferable to use it as it facilitates the action of the bars 30 and 42 to their positions as shown in Fig. 1. The principal function of the weight 40, however, is to maintain the 7 bar 30 in its left-hand position while the door is open so that at this time the bolt 33 cannot be thrown through or into the lock casing.

It will now be explained that so long 7 as the bolt 33 is not in its locking position, an elevator car cannot be started away from a landing. That is, before the car can start, the door must be closed, the spring 18 allowed to force the parts into positions 80 shown in Fig. 2, and the bolt 33 projected through the opening 34 to locking position. Referring therefore to Figs. 3 and 9, it will be seen that an electro-magnetic cam mounted on the car co-acts with the door lock and 85 also operates a circuit closer controlling electric hoisting apparatus. The apparatus in Fig. 9 is merely to illustrate an application of my invention. Other electro-magnetic cams than that here shown may be 90 used and any desired system of wiring and hoisting apparatus may be employed.

Back of the door jamb 48 I mount an angle iron 49 having bearings 50 and 60 for a rock shaft 51. Adjacent the bearing 50 a 95 lever arm 54 is secured to the rock-shaft 51, and at the lower end of this arm is pivoted the locking bolt 33. The arm 54 is preferably adjustable along the shaft 51 so that after having once secured the keeper casing 100 in the door jamb and the angle-plate 49 in the hoistway the position of the lock bolt 33 may be adjusted. Secured to rock shaft 51 near the bearing 60 is an additional arm 53 as shown in Fig. 3. The outer end 56 of the arm 53 engages a U-shaped recess 57 in the short arm 58 of a lever 59 pivoted on a bearing 52 secured to the plate 49. The lever 59 is in reality a bell-crank its longer 105 arm 62 extending upwardly and carrying 110 at its outer end an anti-friction roller 61 which is adapted to be engaged by the vertical cam 63. This cam is flared outwardly at 64 and 65 so that there will be no uncertainty as to the roller 61 riding in the cam groove when desired. It will be noticed that the cam is open only on that side facing the angle plate 49. To its closed side are pivoted the link 73 and the lever 96 as indicated in Fig. 9.

115 It should be particularly noted that it is a distinct advantage to have the apparatus operated by the cam mechanism located in the way shown in Fig. 4, for the reason that the doors and door locks may not be in vertical alignment along the hoistway but nevertheless they may easily be brought into operative position relative to the cam mechanism by moving the arm 54 toward or from the arm 53. The arm 53 may also be ad- 120 125 130

justed along the shaft 51 if necessary to bring it opposite the bell-crank 59. The cam 63 being carried by the car will therefore be able to engage any of the rollers 61 which must be in substantial vertical alinement. If the keeper casings are not in vertical alinement the angle plate 49 may be varied in length or the lever 54 may be shifted along the shaft 51 until the proper adjustment is secured. Furthermore, it should be noted that the mechanism for actuating the locking bolt 33 is located in a place which is practically inaccessible from the car or a landing. Besides, this actuating mechanism projects into the well at a point where it is unlikely to be crowded by the car, for it is placed to one side of the car travel where the usual guideways necessitate a certain space which has been heretofore practically unavailable for any useful purpose except wiring.

When the locking bolt 33 locks the door, as shown in Fig. 3, a spring-pressed circuit-closing plate 66 connects the contacts 67 and 68 which are connected to the binding posts 69 and 70, respectively, and mounted on the insulation 97. This circuit closer is on the car and is controlled by the electro-magnetic cam, so that the car cannot start unless said circuit closer is in closed position. This is illustrated in Fig. 9 wherein C designates an elevator car connected by the hoisting cable 99 over a sheave 100 to the hoisting apparatus 101 which is adapted to be operated by the electric motor 102. B designates the brake mechanism; R, R', the reversing switches; S, the manual controlling switch in the car; and M, the magnetic cam connected in any suitable manner to the car. The solenoid 103 of the cam M is connected to the car switch in such manner that whenever the switch is moved to operating position the said solenoid will be excited to lift its core 104 and effect a movement of the cam 63 to the right. The cam 63 may be of a length about equal to the height of the car or it may be made of any other convenient length. When the cam 63 is moved to the right the circuit closer 105 which is also carried by the car is closed and consequently a circuit is closed from the + main, and by way of suitable circuits through the circuit closer 105 and one or the other of the reversing switch magnets, the car switch 55 and thence to the - main. It will be noticed that the solenoid 103 is connected directly across the mains. Upon the closing of the selected reversing switch the electric motor 102 and brake mechanism B will be operated to effect the actuating of the hoisting apparatus in the desired direction.

It is now apparent that when the switch S is brought to central position the car will be stopped, the core or plunger 104 will drop to move the cam 63 to the left and

thus open the circuit closer 105 and withdraw the locking bolt 33 so the elevator door can be opened. Obviously the door locking apparatus may be so constructed that before the circuit closer 105 can be closed the door must be fully locked, and conversely the circuit closer 105 opened before the door is unlocked. In any event the relation of parts should be such that when the door is open and therefore the lug 32' is in the path of the bolt 33 the cam 63 cannot be moved a sufficient distance to the right to allow the circuits for the reversing switch magnets to be closed. While the car is being moved past a floor the cam 63 rides over the roller 61 of the locking mechanism at that floor. In order to allow the car to come to a gradual stop the cam should be of a reasonable length for even after being moved to its dotted line position as shown in Fig. 3 at 64' it may still ride over the roller 61' for a short distance of travel of the car in coming gradually to rest.

In Figs. 5, 6, 7, and 8, I have shown locking mechanism embodying my invention applied to sliding doors. In the keeper casing 1' is movably mounted a frame 75 which is held in its uppermost position by the spring 92 between the cups or recesses 91 and 93. The upper portion 74 in this instance is shown narrower than the lower portion of the frame 75 and is adapted to move in the recess 76 at the upper part of the casing 1' in the path of the locking bolt 33. When the sliding door is open the lock casing 2' occupies a position off to the right and the bolt 33 cannot be projected into the keeper casing 1' through the opening 34' a sufficient distance to allow the circuit closer 105 (Fig. 9) to be closed, the projection 74 being held by the spring 92 in the path of said bolt. The frame 75 has an opening 77 of such size and shape as to permit the insertion of the head 78 of the locking lever 95 which is pivoted to the lock casing at 79. 86 designates a cam which curves downwardly and is herein shown as forming part of the keeper casing 1'. The under side of the cam is inclined and is adapted to fit a corresponding inclined surface 87 just below the opening 85 in the lock casing 2'. A frame 89 carries a screw 88 for limiting the downward movement of the lever 95. This screw may be adjusted by inserting a screw driver through the bottom of the casing 2' and turning the screw head 90. The lever 95 is held against the stop 88 by means of the comparatively strong spring 82 which is held in place by the lug 83. When the door is closed the head 78 rides over the surface of the cam 86 to move the lever 95 upwardly, thus placing the spring 82 in tension. The opening 84 in the face plate 3' being in alinement with the opening 77 in the frame 75, 130

the head 78 will readily enter the keeper casing as shown in Fig. 5. As soon as it has done so, however, the spring 82 acts to snap the lever 95 in locking position by 5 moving the frame 75 to its lowermost position against the spring 92, as shown in Fig. 6. Now the locking bolt 33 may be moved a sufficient distance to effect the closure of the circuit closer 105 (Fig. 9) 10 and the elevator car may be started.

While the bolt 33 is in its locking position as indicated in Fig. 8 the frame 75 cannot be moved upwardly a sufficient distance to allow the head 78 to be withdrawn 15 or the door opened. When the bolt 33 is withdrawn which can occur only when the car is opposite the landing door, the spindle 81 may be turned clockwise to rock the lever 80 and consequently lift the head or catch 78 20 to the position shown in Fig. 5 when the door may be readily opened.

Obviously those skilled in the art may make various changes in the details and arrangement of parts without departing from 25 the spirit and scope of my invention, and I do not desire to be limited, therefore, to the precise construction herein shown and described.

What I claim and desire to have protected 30 by Letters Patent of the United States is:

1. The combination with a car, of a door, means for operating the car, a switch controlling said operating means, a door latch, a latch-holding device, means for operating 35 said latch into position to engage said latch-holding device and hold the door closed, and means first to lock the latch in said holding position, and then operate said switch to start the car.

2. The combination with a car, of a door, a door latch, a manual device for operating the latch, means for operating the car, a switch carried by the car for controlling 45 said car-operating-means, and means for first locking the door latch and then closing said switch to effect the starting of the car.

3. The combination with a car and operating means therefor, of a door, a spring latch for the door, a manual device for releasing the latch, means for locking the latch, a switch separate from the locking-means, and means for successively operating 50 said locking-means and said switch to lock said door before the car can be operated.

4. The combination with a car and operating means therefor, of a door, a manually operable latch for the door, locking-means for said latch, a switch carried by the car, and means for operating said locking means 55 to lock the door and thereafter operate said switch to effect the operation of the car.

5. The combination with a car, of operating means therefor, a door, means for locking said door, a switch separate from said locking-means for controlling the car-op- 60

erating-means, and a magnetic cam for operating said locking means and said switch.

6. The combination with a car, of operating means therefor, an electric switch carried by the car for controlling said operating means, a door, a spring latch and co-operating keeper, a lock for said latch, and means controlled from the car for operating said door lock into position to prevent the said latch from being dis-engaged from its keeper, and thereafter closing said switch to effect the operation of the car. 75

7. The combination with a car, of operating means therefor, a door, means for locking said door in closed position, an electric switch separate from said locking means, a cam for operating said door-locking-means and said switch in the order mentioned, a motor for actuating said cam, and means carried by the car for controlling said motor. 80

8. The combination with a car, of operating means therefor, a door, door-locking means, a switch carried by the car for controlling said car-operating-means, an electromagnetic cam for operating said door-locking-means and said switch, and an additional switch for controlling said electromagnetic cam. 85

9. The combination with a car, of operating means therefor, a door, a latch for the door, manually operable means for operating the latch, locking means for said latch, a switch separate from said locking means controlling said car operating means, mechanism for operating said locking means and said switch when the door is closed, and means co-operating with said mechanism for preventing the operation of said switch when the door is open. 95

10. The combination with a car, of operating means therefor, a door, a manually operable spring latch for the door, a lock for said latch, a device separate from the lock for controlling said car-operating-means, and automatic means for successively operating said device and said lock when the car 100 is brought to rest opposite such door.

11. The combination with a car, of operating means therefor, a door, a hand operated latch, a door-lock, a switch separate from said lock for controlling said car-operating-means, means for successively operating said lock and said switch, and means in the lock 115 for preventing the operation of said switch when the door is open.

12. The combination with an elevator car, of means for moving same, a well door, a manually operable latch therefor, locking mechanism for said door, a device independent of the locking mechanism for controlling 120 said moving means, and means for successively operating said locking mechanism and said device.

13. The combination with an elevator car, of hoisting apparatus therefor, means for 125

- operating said hoisting apparatus, a well door, locking mechanism for said door, a switch carried by the car for controlling said operating-means, an electro-magnetic cam 5 carried by the car for operating said locking mechanism and said switch, and manual means carried by the car for controlling the operation of the hoisting apparatus and the operation of said electro-magnetic cam.
- 10 14. In an elevator, the combination with a car, of a door, a door lock, a rock shaft mounted back of the door jamb, a rock arm on said shaft and pivoted to a part of the door lock, a bell crank lever, a movable vertically arranged channel shaped cam carried at one side of the car and engaging one arm of the bell crank lever, and a second rock arm on said rock shaft and in engagement with the other arm of the bell crank lever.

15. In an elevator, the combination with a 20 car, a door, a door lock comprising a bolt movable into and out of position to lock the door, a rock shaft back of the door jamb, a lever secured to said shaft and pivoted to said bolt, an additional lever carried by said 25 shaft, a bell crank connected to said additional lever, and means carried by the car for actuating said bell crank to effect the operation of said door lock.

In testimony whereof, I have signed my 30 name to this specification in the presence of two subscribing witnesses.

ANDREW M. COYLE.
